FULL FASHIONED HOSIERY

John M. Botts, Jenkintown, Pa.

Application July 15, 1936, Serial No. 90,633

2 Claims. (Cl. 66—172)

This invention relates to full-fashioned hosiery of the type in which the top section, that is, the section corresponding to the doubled over welt of an ordinary full-fashioned stocking consists 5 of a single layer of fabric, and coordinately therewith it relates to a method of making such hosiery.

While my invention has been disclosed in connection with full-fashioned hosiery, it is to be understood that as to certain phases thereof it 10 may have other applications.

In the manufacture of full-fashioned hosiery of the type which forms the subject of this invention, in which the top portion consists of a 15 single layer of fabric, it is customary to form a complete stocking blank without removing the blank from the machine. That is to say, once the initial loops are formed on a needle bar, corresponding to the welt bar used in the formation of ordinary full-fashioned hosiery, the blank 20 is not removed from the machine until the knitting thereof is completed.

As a result of this method of knitting, in which only a single machine is used, the variety 25 of patterns or designs in the different sections of the stocking is of necessity limited because a knitting machine of the ordinary type has only a limited capacity for pattern adjustment, and where it is desired to have a great variety of 30 patterns in a single stocking blank, a resetting of the pattern adjustment is necessary during the course of knitting the blank. Since this resetting is an expensive operation, necessitating the stoppage of the machine, a great variety in 35 the patterning of stockings manufactured in the customary manner is excluded.

It is among the general objects of my invention to provide for a greater variety of pattern in a full-fashioned stocking by knitting a portion 40 of a full-fashioned stocking blank separately from the other portions of the blank, in machines particularly adapted to knit only this portion, and finishing the blank in a different machine or machines.

It is further among the objects of my invention to provide for continuous quantity production 45 of such separately knitted sections, thereby greatly reducing the cost thereof.

It is also an object of my invention to provide 50 a method of manufacturing full-fashioned hosiery whereby a portion thereof is first manufactured in quantity, after which it may be stored for future use, as desired, and thereafter have the other portions of a stocking added thereto. It is also an object, in connection with 55

the method just described, to provide for associating with a portion of a stocking having a particular pattern or design, other portions that may be different in pattern from each other and from said first mentioned portion. 5

For the attainment of these objects and such other objects, as will hereinafter appear or be pointed out, I have illustrated one embodiment of my invention and one manner of practicing the same in the drawing; in which: 10

Figure 1 is a plan view of a fabric strip knitted according to my invention; said strip being composed of a plurality of "repeat" sections;

Figure 2 shows one of the "repeats" of the fabric strip of Figure 1 separated therefrom and 15 ready for insertion into a flat bed knitting machine;

Figure 3 is intended to indicate the manufacture of a stocking blank after the blank section of Figure 2 has been inserted into a flat bed 20 knitting machine; and

Figure 4 is intended to illustrate a finished stocking, however before the ravel-off section has been removed.

My invention will first be described in broad 25 outline. In the practice thereof as hereinafter described in detail, I first knit on a flat-bed knitting machine a strip of fabric involving a repetition of a section of a full-fashioned stocking, and each such repetition or "repeat" is 30 readily separable from the strip and further is so made that it may be placed into another flat-bed knitting machine in which it may have knitted portions added thereto.

The advantages of this procedure reside in the 35 fact that the "repeat" strip may be produced in quantities, and therefore cheaply, even though it involves the production of a complicated knitted pattern, because each "repeat" is of relatively small area and therefore requires only a 40 relatively small machine, which need not be unduly complex to provide the adjustments needed to produce the pattern of each "repeat", even though it be of a design, ordinarily considered difficult to produce. This machine would 45 require adjustment only before the commencement of production and thereafter the "repeat" strips may be continuously produced, without further adjustment. After completion of the strip it may be stored in strip form, to be made 50 up into stockings as desired.

The practical advantages of my invention may now be pointed out. Suppose a department store wishes to have its name embroidered 55 into stockings sold by them. To have this done

by the ordinary processes of manufacturing hosiery would be impractical because the cost would be prohibitive even if a large quantity were ordered. To order a large quantity, beyond immediate requirements would involve the investment and the tieing up of a considerable amount of capital. However the department store might order a large quantity of "repeat" strips made in accordance with my invention, at relatively low cost and capital outlay and store these for use as needed. In accordance with the demand a portion of these strips may be used in making up completed stockings for immediate sale, the department store for that purpose sending the necessary quantity of "repeats" to a stocking factory of their selection, while the remainder is held in reserve for future requirements.

Referring now to Figure 1 it will be observed that I there show a plain knitted fabric strip comprising at the extreme left a section 10 that is intended to be a ravel-off section, that is a section that is to be removed and constitutes waste, and for that reason is preferably knitted of the most inexpensive material suitable for the purpose. This ravel-off section is followed by a section 12 which is to constitute the top part (or the part corresponding to the welt section of an ordinary stocking) of a stocking made according to my invention, and which is therefore knitted with "finish" thread. Succeeding portions of the strip are constituted by a repetition of the sections just described, and to show this relation they have been designated by the numerals 10 and 12, used for the first sections, however, with superscripts added.

Each section 12, 12', etc., is shown as commenced by one or more courses of self-locking loops or ravel proof loops (picot loops) 13, 13', etc., and at its other end is terminated by a course of transfer loops 16, 16', etc., such courses having the well known purpose of permitting the introduction of the section into a flat bed knitting machine for the purpose of adding knitting thereto in continuation of the strip. It will be understood, that in order to remove the ravel-off sections 10, 10', etc., it is only necessary at the desired stage of manufacture, to cut across a course or courses of the ravel-off sections, to separate the courses, and then use the course, so freed at the desired point, as a "pull-course". When this pull course is removed the sections separate.

Due to the fact that the strip consists of repeats of small area it is possible to set a moderate sized knitting machine so as to knit rather complicated patterns. For example, Figure 1 shows, by way of illustration, a hypothetical dealer's name, "Smith & Co.", knitted into the section 12. Instead of a name, of course, patterns of various other types may be so knitted.

In the manufacture of hosiery according to my invention, each strip, as shown in Figure 1, is separated, as just described, by pulling out one of the courses, into portions each comprising a section 10 and 12, these sections remaining

united. The transfer loops 16 may then be placed on a transfer bar 18 as shown in Figure 2, and the fabric portion consisting of sections 10 and 12 introduced into a knitting machine, as indicated in Figure 3, in which a hook bar 20 has been shown as used to apply tension to the section 10, by means of an arrangement involving the take-up roller 22, carried by the machine, over which passes a strap 24, connected by tension equalizing springs 26 to a second strap 28 attached to the hook bar 20. A section 17 of knitted fabric has been shown as forming a continuation of the strip 12, the knitting of this section 17 having been commenced at the transfer loops 16. Thereafter the knitting is continued until a complete stocking blank has been formed, which is then seamed to form a stocking, and thereafter may be dyed and boarded in the customary manner, until a product as shown in Figure 4 results, which is a finished stocking except that the ravel off section 10 is still in place thereon. This ravel off section may then be removed by cutting along the seam, so as to separate the courses thereof, and by pulling out the course nearest to the picot loops 13 forming the top of the stocking, whereby the ravel off section 10 drops off and the stocking has assumed its final form.

It is unnecessary to go into further details relating to these latter steps of manufacture, as they have been fully described in my Patent No. 1,833,705, November 24, 1931.

While I have described the ravel-off section 10 as retained on the stocking until after the boarding operation, for reasons that have been disclosed in my aforementioned patent, it is to be understood that if desired, it may be removed at any intermediate stage, where found desirable.

While I have herein disclosed illustrative embodiments of my invention and an illustrative manner of practicing the same, it will be obvious that the same may be embodied in many other forms and practiced in many other ways, as will be obvious to those skilled in the art, without departing from the spirit thereof, and that I do not limit myself in relation to the scope of the disclosure herein other than as called for by the prior art.

Having thus described my invention and illustrated its use, what I claim as new and desire to secure by Letters Patent, is:

1. As an article of manufacture, a knitted strip comprising a plurality of sections, each of said sections adapted to serve as a single layer welt of a full-fashioned knitted stocking, said sections alternating with ravel-off sections, each of said first-mentioned sections being terminated at an end thereof by at least one course of picot loops.

2. As an article of manufacture, a plain-knitted strip comprising a plurality of sections, each adapted to serve as a single-layer welt for a full-fashioned knitted stocking and each being terminated at one end by at least one course of picot loops and on the other side by at least one course of transfer loops, and a ravel-off section between each pair of said first-mentioned sections.

JOHN M. BOTTS.
